PIPE

Filed April 8, 1926

Fig: 1.

Eugene Lucas INVENTOR
BY C. Campbell & Sonnleitner

ATTORNEY

UNITED STATES PATENT OFFICE

EUGENE LUCAS, OF BABYLON, NEW YORK

PIPE

Application filed April 8, 1926. Serial No. 100,484.

This invention relates to a tobacco pipe.

In smoking the usual form of pipe comprising a bowl and a stem with a hole through the stem to the bowl, the smoker finds that the bowl becomes hot and the hole in the stem clogs up. In addition, after a period of time the pipe cakes and unless the cake is cut out eventually causes a breakage of the bowl.

One of the objects of this invention is to decrease the temperature of the outer walls of the bowl. Another object of the invention is to prevent radiation of heat to a smoke well below the tobacco bowl. Still another object of the invention is to provide a pipe that will smoke satisfactorily at a low cost of manufacture. A further object of the invention is to provide a pipe that can be easily cleaned and one that will not cake although smoking in a cool manner similar to a well caked pipe. Still other objects of the invention are to provide a pipe that will retain the heat within the inner bowl to more entirely consume the tobacco and be sanitary at the same time and give a cool, clean smoke.

25 Referring to the drawing:

Figure 1 is a longitudinal sectional view partly in elevation embodying the principles of my invention.

In carrying out my invention, I propose 30 to make the bit preferably of hard rubber although any of the well known materials of which pipe bits are made can be used. A hole or smoke conduit 2 is drilled therethrough in the usual manner and bit 1 is preferably made 35 tapered as at 3 to fit within the protruding stem 4 from the pipe. I also propose to make the pipe proper of clay which comprises an inner bowl 5 terminating at the top in a collar 6 and having a passage 7 from the bottom 40 thereof to smoke well 8. Adjacent bowl 5 is bowl 9 made principally of magnesium. Around bowl 9 is the pipe body 10 formed of two parts, 10' and 10''. The body part 10', contains within itself bowls 5 and 9. The 45 three bowls 5, 9, and 10', are pressed into an integral unit while in a plastic state and then glazed or vitrified both inside and outside to make the unit non-porous. The lower part 10'' is likewise glazed or vitrified to make it 50 non-porous. The lower portion 10'' contains

smoke well 8 and pad 11 which may be of antiseptic material. The lower portion 10'' is made integral with the stem 4. Upper portion 10' and lower portion 10'' are threaded together at 12.

The inside of bowl 5 is preferably glazed to prevent burning or charring and its saturation with nicotine. It will be noted that such construction prevents the formation of heels of saturated tobacco or the formation of cakes in the bowl.

The inner bowl 9 of magnesium reduces the radiation and transfer of heat from bowl 5 to the outer portions 10', 10'', and smoke well 8.

Smoke well 8 not only operates as a cooling chamber, but also prevents moisture from the mouth from reaching the tobacco and such moisture is absorbed by pad 11. The glazing of the walls of smoke well 8 prevents the absorption of moisture making the pipe more sanitary.

The tobacco burning in bowl 5 radiates the majority of its heat out of the top of the pipe giving a more satisfactory smoke. The clay pipe can be colored or decorated exteriorly with artistic designs and glazed if desired.

It will thus be seen that I have invented a pipe that can be readily cleaned by the flushing with water or, if desired, can be taken apart and easily cleaned and one that is cheap to manufacture, giving a satisfactory, pure, clean and cool smoke.

What I claim is:

1. A clay pipe comprising a bit, a stem and a bowl, said bowl formed into an integral unit from three bowls while in a plastic state, said bowl comprising an inner clay bowl glazed on the inside, an outer clay bowl glazed on the outside, a magnesium bowl between said inner and outer bowls, a smoke passage-way from said inner bowl through said outer bowl, stem and bit.

2. A clay pipe comprising in combination a bit, a stem, a body portion formed in the plastic state of three bowls into an integral unit and glazed internally and externally, said body portion consisting of an inner bowl, an outer bowl, and a lining between said inner and outer bowls of heat insulating material.

3. A clay pipe comprising a bit, a stem and a body portion, said body portion separable from said stem and adapted to be threaded therein, said body portion formed in the plastic state into an integral unit of three bowls, said bowls comprising an inner bowl and a bowl of heat insulating material between said inner and outer bowls, said body portion glazed internally and externally, 10 said stem glazed internally and externally, a smoke passage between said body portion and said stem and a smoke passage through said stem and said bit.

4. A clay pipe comprising a bit, a stem and a body portion, said body portion separable from said stem and adapted to be threaded therein, said body portion formed in the plastic state into an integral unit of three bowls, said bowls comprising an inner 15 bowl and a bowl of heat insulating material between said inner and outer bowls, said body portion glazed internally and externally, a smoke well in said stem, a smoke passage from said body portion to said smoke well, 20 a smoke passage through said stem through said smoke well communicating with a smoke passage in said bit, said stem glazed internally and externally.

5. A clay pipe comprising a bit, a stem and a body portion, said body portion separable from said stem and adapted to be threaded therein, said body portion formed in the plastic state into an integral unit of three bowls, said bowls comprising an inner 30 bowl, an outer bowl and a bowl of heat insulating material between said inner and outer bowls, said body portion glazed internally and externally, a smoke well adapted to receive an asbestos pad, an asbestos pad 35 for said smoke well, a smoke passage from said body portion to said smoke well, a smoke passage from said smoke well through said stem and communicating with a smoke passage in said bit, said stem glazed internally 40 and externally.

Signed at New York, in the county of New York and State of New York, this 2nd day of April, A. D. 1926.

EUGENE LUCAS.
